To all whom it may concern:

Be it known that I, Gerhard R. Schutes, a citizen of the United States, residing at Saginaw, in the county of Saginaw and State of Michigan, have invented a new, original, and ornamental Design for Combination Vanity and Writing Desk with Clothes Hamper Seat, of which the following is a specification, reference being had to the accompanying drawing, forming part thereof.

In the drawing:

Fig. 1 is a perspective view of a combination vanity and writing desk with clothes hamper seat, looking downwardly toward one corner thereof,

with the parts in nested relation, and showing my new design.

Fig. 2 is a similar view on a smaller scale with the seat in spaced relation to the combination vanity and writing desk.

The opposite side of the design from that illustrated is substantially the same as the side illustrated.

I claim:

The ornamental design for a combination vanity and writing desk with clothes hamper seat, as shown and described.
